(57) **CLAIM**

The ornamental design for a thermostat, as shown and described.

DESCRIPTION

FIG. 1 illustrates a perspective view of a thermostat; FIG. 2 illustrates a top view of the thermostat of FIG. 1; FIG. 3 illustrates a bottom view of the thermostat of FIG. 1; FIG. 4 illustrates a front view of the thermostat of FIG. 1; FIG. 5 illustrates a back view of the thermostat of FIG. 1; FIG. 6 illustrates a left side view of a thermostat of FIG. 1; and, FIG. 7 illustrates a right side view of a thermostat of FIG. 1. The broken lines are included for the purpose of illustrating portions of the thermostat and form no part of the claimed design.
